UNITED STATES PATENT OFFICE.

FRITZ ALDENDORFF, OF BERLIN-WILMERSDORF, GERMANY, ASSIGNOR OF ONE-
FOURTH TO PAUL KOLISCH, OF NEW YORK, N. Y.

AUTOMATIC SWITCHING.

Application filed February 14, 1922, Serial No. 536,504, and in Germany April 5, 1921.

This invention relates to automatic switching systems and more particularly to such systems as are employed for interconnecting telephone lines.

6 A feature of the invention is that the wanted lines are first connected by wanted line-selectors composed of a group of small switches whose number of bank contact points is smaller than the number of contact points in the banks of talking-connection and called-line-finders that are set onto the selected wanted lines by means of the said wanted line-selectors. For example talking-connection called-line-finders with contact banks for 100 wanted lines may be steered onto anyone of the 100 wanted lines by two small wanted line-selectors having only 10 bank contacts or contact sets each.

The invention also relates to an electro-mechanical telephone system in which the subscribers' lines are divided into groups of say 100 lines each and in which the talking connections are established by talking connection switches in the form of calling-line-connectors, wanted-line-connectors, and trunk-connectors intermediate between the calling-line and wanted-line-connectors, all of which connectors are set onto the proper line or trunks by the aid of transitorily engaged switches which revert to common use as soon as they have performed their functions of setting the talking-connection switches onto the proper subscribers' lines and trunks.

35 The transitorily engaged switches comprise calling-line-finders, group-selectors, wanted-line-selectors, and a small number of small auxiliary switches. The number of transitorily engaged switches is proportionate to the highest number of dialling or connection-establishing operations that occur at one and the same time, and the number of talking-connection switches is proportional to the largest number of simultaneous conversations.

50 The invention also relates to switching devices which will act satisfactorily, under all conditions of service, as a line-finder, selector or connector. This object is accomplished by constructing the switch in such a manner that its movable contacts move or jump in one quick step straight into the

group of bank contacts in which the line or trunk to which the connection is to be made, is located, whereupon the movable contacts are moved at a slower speed until the wanted line is reached.

55 Other features of the invention will appear in the specification and drawings.

The drawings show the circuits of a system in which the talking-connections are established by talking-connection-switches in the form of calling-line-connectors, wanted-line-connectors, and trunk-connectors intermediate between the calling-line and wanted-line-connectors, and all of which connectors are set onto the proper lines or trunks by the aid of transitorily engaged switches. A complete layout and diagram of the circuits of the novel system is obtained by putting Figs. 1—9 together in the manner indicated in the left bottom corner of Fig. 3.

60 S¹ in Fig. 1 represents the calling subscriber and S₁, Fig. 8 represents a wanted subscriber.

65 Each group of 100 subscribers may be equipped with three groups of 100-point talking connection switches comprising 10 calling line connectors CC¹, CC², etc. 10 trunk extending switches or trunk connectors TC¹, TC², etc.

70 10 wanted line connectors WC¹, WC², etc. and seven groups of small transitorily engaged switches comprising:

75 2 (or more) calling line finders CF¹, CF², etc.

2 (or more) group selectors GS¹ GS², etc.

2 (or more) wanted line selectors WS¹, WS², etc. (Fig. 9)

2 (or more) primary trunk finders PT¹, PT², etc. (Fig. 1)

2 (or more) group selector finders GF¹, GF², etc. (Fig. 7)

2 (or more) secondary trunk finders ST¹, ST², etc. (Fig. 6)

2 (or more) auxiliary finders AF¹, AF², etc. (Fig. 6).

80 In addition to these there may be a calling line identifying device CJ, Fig. 2, and a wanted line identifying device WJ.

85 To the pairs of switches ST¹, AF¹ and ST², AF² are assigned (in addition to their functions of connecting engaged wanted line connectors WS to secondary trunks st¹, st²

etc.) the functions of identifying the proper secondary trunks to which the trunk connectors TC, Fig. 3, must connect in order to correctly establish talking connections prepared by the transitorily engaged system. This will be hereinafter more fully described.

Each calling line connector CC, Fig. 1 has four wipers and four corresponding rows of 100 bank contacts each. The bank contacts of each group of calling line connectors CC are connected in multiple and to 100 subscribers' lines. One of the bank contact rows of each calling line connector CC is connected in multiple with the corresponding rows of the other calling line connectors and also with a row of bank contacts in each of the calling line finders Cf of the same group.

The trunk connectors Tc, Fig. 3, have five wipers each which are arranged to return to a definite normal position whenever they are released. The calling line connectors CC have no definite normal position. The bank contacts of the trunk connectors TC are divided into ten groups of ten contact sets each. At the beginning of each row of ten contact sets there is a preliminary contact which marks the group of contact sets into which the five wipers of the switch are to be moved. Associated with each trunk connector TC is an auxiliary selector GS which has one wiper only that is restored to a definite normal position whenever the switch is released. The wiper of the auxiliary or group marking switch is arranged to make contact with anyone of ten bank contacts. These latter are each connected to a corresponding preliminary contact in the bank of the associated trunk connector TC. The contact sets of the banks of the trunk connectors TC of the ten different 100 groups of the exchange are all connected in multiple, it being assumed that the system described herein is for 1,000 lines, although the same system could of course be used for larger exchanges.

Each called line connector WC is provided with four wipers that are restored to their normal position when the switch is released. The contact bank of each of these switches has four rows of bank contacts, the contact bank being divided into ten groups of ten contact sets each. At the beginning of each group there is a preliminary group marking contact. The bank contacts of the called line connectors of one and the same 100 groups are all connected in multiple. The subscribers' lines of each particular 100 group are associated with three bank contact rows of each switch WC of the corresponding 100 group and the fourth row of bank contact as well as the preliminary contacts are connected to the wanted line selectors WS of the corresponding 100 group.

The calling line finders CF are each provided with a plurality of sets of wipers, there being a plurality of wipers that hunt simultaneously for calling lines. The contact bank for 100 lines may be divided into say 5 groups of 20 lines each and each one of five different wipers may hunt for a line in its particular group. By this means every one of 100 lines may be tested in 20 steps. Associated with each of the simultaneously hunting wipers of a calling line finder is a test relay T and for each group of test relays T there is a common relay S. In Fig. 2 each calling line finder is represented with three simultaneously hunting wipers and three corresponding test relays T₁, T₂, T₃. Of these test relays only one can be energized at one and the same time because means are provided for preventing the energization of more than one test relay in case a plurality of simultaneously hunting arms strike upon calling lines at the same moment. When a test relay is energized a calling line is connected through to a free group selector GS. When several calls are made in the same group at the same time each call is connected through to a different group selector GS. Whenever a call is made all the calling line finders CF are started together. The order in which the calling lines are connected to the contact banks may be different in the different calling line finders so that each finder will test different lines when the finders operate simultaneously.

Each group selector GS has seven wipers which are restored to normal whenever the switch is released. The bank of each group selector has ten sets of seven contacts each. The first five contacts of each contact set, counting from the right, is connected to wires that lead to a certain wanted group. Thus the first five contacts of the first set lead to the first 100 group, the first five contacts of the second set lead to the second 100 group and so on. These bank contacts of the group selectors GS are not connected in multiple. The sixth and seventh contact of each set are connected in multiple with the corresponding contacts in the banks of the other group selectors in the exchange.

The wanted line selectors WS have only two wipers each which are restored to normal when the switch is released. For each of the wipers of the wanted line selectors there is a single row of ten bank contacts and the corresponding rows of the contact banks of the wanted line selectors are connected in multiple. The multiples connected to the bottom rows of the banks of the switches WS are connected to the inner row of each group of each bank of the wanted line connectors and the multiples of the top rows of the banks of the wanted line selectors WS are connected in multiple with the

preliminary contacts at the beginning of each group of contacts in each bank of the wanted line connectors WC as shown in Fig. 8.

- 5 The primary trunk finders PT have six wipers each and six corresponding rows of bank contacts. The number of contacts in each row being equal to the number of talking trunks *pt* with which they cooperate.
- 10 The primary trunk finders PT have no definite normal position.

The secondary trunk finders ST, Fig. 6, have five wipers each with corresponding rows of bank contacts, the number of contacts in each row being equal to the number of secondary talking trunks *st* with which the secondary trunk finders ST cooperate. The secondary trunk finders ST have no definite normal position. Associated with 20 each secondary trunk finder ST is a dialling trunk finder AF. Each finder AF has five wipers and five corresponding rows of bank contacts. The number of contacts in each row is equal to the number of dialling trunks 25 or wanted line selectors WS. The dialling trunk finders AF have no definite normal position.

The identifying device CJ, Fig. 2, has three wipers and three corresponding contact rows in its contact bank. The number of contacts in each row is equal to the number of dialling trunks or group selectors GS.

The identifying device WJ, Fig. 9, is also provided with three wipers and the number of bank contacts in each row is equal to the number of dialling trunks or wanted line selectors WS. Neither of the identifying devices has any definite normal position.

All of the above-mentioned selectors or switches and identifying devices are unimotional and their contact banks may be circular or straight as in switches of the panel type.

The group selector finders GF are each provided with a plurality of sets of wipers with five wipers in each set. Each set of wipers cooperates with ten different sets of bank contacts. The sets of corresponding groups of bank contacts of the different 45 group selector finders are connected in multiple with each other. The contact bank multiples of the group selector finders GF lead to contact sets in the contact banks of the various group selectors GS in the exchange. The first five contacts (counting from the right) of the group selector GS¹ of the first group of the exchange are connected to the first set of contacts in the bank of each group selector finder GF¹, GF², etc. 50 of the first group of the exchange. The first five contacts of the second set of the bank of the first group selector GS¹ of the first group lead to the first set of contacts in the bank of each group selector finder (similar to GF¹, GF²) of the second 55

group of the exchange. The first five contacts of the first set of the contact bank of the second group selector GS² of the first 100 group lead to the first set of the second contact group of each group selector finder GF¹, GF², etc. of the first 100 group and the second set of contacts in the bank of the group selector GS² leads to the first contact set of the second contact group of the bank of each group selector finder (similar to GF¹, GF², etc.) of the second group of the exchange and so on. The contact sets of the contact banks of the group selectors GS¹, GS², etc. of the second, third, fourth and other 100 groups of the exchange 75 are connected in a corresponding manner to the banks of the group selector finders of all the 100 groups in the exchange as will be more fully explained hereinafter with reference to the drawings.

As the group selector finders GF, Fig. 7, are each provided with a number of simultaneously hunting wipers which have no definite normal position the calls extended through the group selectors GS to the group selector finders GF will be generally picked up after the finders have executed only a few steps. In many cases the finders will not need to move at all. Means are provided for preventing a number of calls from being extended to one and the same dialling trunk or wanted line selector WS simultaneously and for preventing one and the same call from being extended to two different dialling trunks.

The wiring of the various switches of a 100 group is substantially as follows:

Wires extend from the line relays AR and the auxiliary relays TR associated with the subscribers' lines to the bank contacts of the calling line connectors CC and the wanted line connectors WC of one and the same 100 group. The relays associated with the subscribers' lines have connections that lead to the calling line finders CF of the particular 100 group. These connections include firstly the wires that lead to the operating magnets of the calling line finders CF, the test wires that lead to the test contacts of the calling line finders CF of the particular 100 group and dialling wires through which dialling impulses are transmitted from the line relays through the calling line finders CF to the group selector GS and also to the trunk connectors TC. After a group selector GS has been set onto the set of contacts that leads to the wanted group dialling impulses are sent by means of the line relay through the group selector GS and through a group selector finder GF to a wanted line selector WS, Fig. 9.

Each calling line connector CC is connected through a primary trunk *pt* to a trunk connector TC and from each contact set of the bank of each trunk connector a

secondary trunk *st* leads to a wanted line connector WC. The contact bank of each trunk connector is divided into ten groups and the ten contact sets of each group lead through ten secondary trunks to ten wanted line connectors of a corresponding 100 group.

In the calling line identifier CJ there is a separate bank contact (as 145) for each calling line finder of the particular 100 group and a separate bank contact (as 125) for each primary trunk finder PT. By these contacts battery is applied to only one bank contact of one calling line finder CF and to only one bank contact of one calling line connector CC at a time as will be hereinafter more fully described.

Starting wires for energizing the operating magnets of the group selector finders GF lead from the banks of the group selectors GS, and stopping wires also lead from the banks of the group selectors GS to the banks of the group selector finders.

Associated with each secondary trunk *st* is a separate identifying wire, as *t²*, for each secondary trunk finder ST. These identifying wires are not multiplied at the banks of the secondary trunk finder ST. By means of these identifying wires battery is connected to a bank contact of a trunk connector TC in such a way as to cause the connector to extend a call only to the particular secondary trunk to which a call has been advanced to the said secondary trunk and also to the trunk connector TC that has been affected by the same call. This will be more fully described hereinafter. The identifying circuits for setting the trunk connectors TC onto the proper secondary trunk extend from the secondary trunk finders ST through the said identifying wires, through wipers of the trunk connectors TC and through the primary trunk finders PT, the group selectors GS, the group selector finders GF and the dialling trunk finders AF and back to the secondary trunk finders ST as will be hereinafter more fully described.

The identifying device WJ applies battery to one bank contact in the bank of one wanted line connector and to a wiper of one wanted line connector WC at a time. The identifying wires for doing this lead from the bank of the identifier WJ to the wanted line selector and to the banks of the wanted line connectors on the one hand and through the dialling trunk finders AF and the secondary trunk finders ST on the other hand, as will be hereinafter more fully described. The identifier WJ applies battery to only one wanted line selector WS and to only one secondary trunk finder ST at a time.

The operation involved in establishing a talking connection by means of the system illustrated will now be outlined.

When the subscriber S¹ makes a call by

raising his receiver the line relay AR, Fig. 1, is energized and closes a circuit for the auxiliary relay TR which is a marginal relay and is only partly energized when the subscriber calls.

The auxiliary relay when partly energized causes all the disengaged calling line finders CF of the group to which the calling subscriber belongs to be started and the calling line finder that first puts a set of its wipers onto the contacts corresponding to the calling line connects the dialling wires of this line through to a free group selector GS. The moment the dialling wires are thus connected through, the calling line finders that were set in motion are all stopped. If the wipers of a free calling line finder CF should have happened to be standing on the contacts of the calling line the latter will be connected through at once without the wipers of a calling line finder having been set in motion. If several sets of wipers of one and the same calling line finder each strike upon a calling line or happen to be standing upon such lines a call will be connected through over one set of wipers only and the other calls will be prevented from being connected through over the other sets of wipers. To this end each finder CF has a separate test relay T for each of its several sets of wipers and a relay S which is common to the relays T. The current lead to the energizing windings of the test relays T passes through a back contact of the common relay S and this lead is disconnected at the said back contact when a test relay together with the relay S is energized so that the current lead to the energizing windings of all the test relays is opened. Before this happens, however, the particular test relay that was energized together with the common relay S forms a circuit for itself through a second winding by which it is maintained energized while opening the lead to the second windings of the other test relays. When a test relay and the common relay in the finder are thus energized they cause their energizing current, which flows over a winding of the auxiliary relay TR of the calling subscriber, to be increased in strength so that the marginal relay TR is now fully energized.

The calling subscriber S¹ now sends in his hundreds selecting impulses and these are translated by the relays AR, TR to the rotary magnet or operating magnet HM of the group selector GS that has been taken into use. The wipers of this group selector are thus set onto the particular set of bank contacts that leads to the desired 100 group in the exchange. These 100 selecting impulses, however, are also sent through the operating magnet D_g in a trunk connector Te and cause the wiper of a group marking switch GS in the trunk connector to be set onto a contact by which the corresponding group of

contacts in the bank of the trunk connector TC is marked. The group selector GS of the dialling trunk is connected before the dialling impulses are sent in by a primary trunk finder PT to a free trunk connector TC.

Let it be assumed that the calling line S¹, Fig. 1, is now connected through the calling line finder CF¹, Fig. 2, to the group selector GS¹, Fig. 4, and through the primary trunk finder PT¹, Fig. 1, to the calling line connector CC¹, Fig. 1, and to the trunk connector TC¹, Fig. 3. It will also be assumed that the group marking switch GS¹ of TC¹, Fig. 3, and the group selector GS¹, Fig. 4, have been set by the hundreds dialling impulses onto their first contact or set of bank contacts, that is to say the calling subscriber desires to establish a connection with a subscriber in the 100 group to which he himself belongs.

The first hundreds impulse gives rise to an impulse that flows through a slow acting relay V¹, Fig. 2, and through the operating magnets HM¹ and D¹ of GS¹, Fig. 4, and GS¹, Fig. 3, respectively. The slow acting relay V¹ keeps its armature attracted until the hundreds impulses have all been sent in and in so doing causes the calling line identifier CJ, Fig. 2, to set its wipers onto the dialling trunk used by the calling subscriber. The said slow acting relay V¹ closes the circuit of the operating magnet D¹ of the identifier CJ whose wipers are thus set in motion. As soon as the contacts corresponding to the dialling trunk used are reached a relay J¹ associated with this trunk is energized together with the test relay T¹ in the identifier. The test relay opens the circuit of the rotary magnet D¹ and thus stops the brushes of the identifier and the relay J¹ closes energizing circuits which extend through the primary trunk finder PT¹ to a relay F¹ in the calling line connector CC¹ thus energizing the relay F¹ which closes the circuit of the operating magnet T¹ of the calling line connector CC¹, Fig. 1. The wipers of CC¹ are thus set in motion. When the identifier CJ is stopped on the dialling trunk used an identifying circuit which is individual to the dialling trunk used and extends through the primary trunk finder PT¹ and through the relay P¹ of the connector CC¹ is prepared and this identifying circuit is closed as soon as the wipers of CC¹ strike the contacts that are connected through the calling line finder used for the connection to the particular dialling trunk to which the calling subscriber was previously connected. The said identifying circuit then energizes the identifying relay P¹ which opens the circuit of the rotary magnet D¹ of the connector CC¹. A relay P¹, Fig. 2, in the calling line finder CF¹ is energized together with the identifying relay P¹ and opens the circuit

of the relay J¹. The operation of setting the calling line connector CC¹ onto the proper line is independent of the dialling operations, i. e. of the 100 selecting impulses of the calling subscriber and may be completed before or after the hundreds impulses have been sent in. Hence, the calling line connector will be able to travel if necessary over its 100 sets of contacts before it is affected by switching operations that occur in the dialling trunk with which it is temporarily associated.

The slow acting relay V¹ that is energized at the commencement of the hundreds impulses also closes the circuit of another slow acting relay W¹ which prepares a circuit for a relay U¹ in the group selector GS¹. When the hundreds selecting impulses have all been sent in and the group selector GS¹ has been set onto the set of contacts corresponding to the wanted group (the first 100 group in this instance) and when the slow acting relay V¹ has had time to fall back, a circuit is closed for the operating magnets D of all the group selector finders GF that happened to be idle at that moment in the desired group. As each of these group selector finders has a plurality of simultaneously hunting wipers, the operation of connecting the calling dialling trunk through to a wanted line selector will only require a few steps to be carried out by the group selector finders. Hence, the calling subscriber will always be rapidly connected through to a wanted line selector WS and there will be no danger of tens selecting impulses sent in by the calling subscriber being lost. As soon as a set of wipers of one of the group selector finders GF, say GF¹, has reached the calling dialling trunk, a test relay, say T¹ in GF¹ is energized and opens the circuit of the operating magnet D of the finder GF¹ so that this finder is stopped. In order to prevent several calls from being connected through to the same wanted line selector in case several sets of brushes of a finder lend upon several calling lines at the same moment a separate test relay T is provided for each set of brushes and the lead to the energizing windings of these relays passes through the bank contact of a relay S which is common to all the individual test relays and which is opened the moment an individual test relay is energized. The particular individual test relay energized establishes a new circuit through an auxiliary winding, but the current leads to all the other test relays are cut off. Thus only one calling dialling trunk is connected through anyone finder and the other calls are extended through other finders GF.

The energizing circuit of the particular test relay, say T¹ operated in the group selector finder GF¹ extends through the relay U¹ in the group selector GS¹ and this relay U¹ opens the energizing circuit of the op-

erating magnets of the group selecting finders GF of the selected group.

The calling subscriber now sends in his tens dialling impulses which are translated by the relay AR, Fig. 1, into the operating magnet ZM¹ of the tens designating switch of the wanted line selector WS¹ to which the call has been extended. The operating magnet ZM¹ steps its wiper *t*¹ onto the tens designating contact, say the first tens designating contact 349, Fig. 9.

The energizing circuit of the operating magnet ZM¹ extends through a slow acting relay VZ¹ which closes the circuit of a relay ST¹ when its armature drops back. The relay ST¹ then cuts out the tens operating magnet ZM¹ and includes the units operating magnet EM¹ in the dialling circuit controlled by the impulse relay JR¹.

20 The slow acting relay VZ¹ that is energized when the tens dialling impulses commence coming in also causes the wanted line identifier WJ to set its brushes onto the dialling trunk used for the connection. The operations involved in this function are similar to those described in connection with the calling line identifier CJ, Fig. 2.

The relay S of the group selector finder GF¹ which was energized when this finder 30 extended the call will now have caused an idle auxiliary finder AF, say AF¹, Fig. 6, to have set its wipers onto the dialling trunk used for the call, i. e. the dialling trunk corresponding to the finder GF¹ and 35 the wanted line selector WS¹. The particular secondary trunk finder ST that is associated with the auxiliary finder AF used for the call will have preselected a secondary trunk, say the trunk *st*¹ that terminates in a wanted line connector WC¹. As soon 40 as a pair of switches, say AF¹, ST¹ has connected an idle wanted line connector WC¹ to the dialling trunk CF¹, WS¹ used for the call, a relay O¹ associated with this dialling 45 trunk is energized and it then closes the starting circuit of the trunk connector TC¹ previously seized for the call. This starting circuit for the trunk connector TC¹, Fig. 3, extends from the relay O¹, Fig. 7, through 50 the group selector finder GF¹ and the group selector GS¹ used for the call and through the primary trunk finder PT¹ to the operating magnet D¹ that moves the brushes of the trunk connector TC¹. The brushes of TC¹ 55 are now moved until they reach the particular secondary trunk which has been connected through a pair of switches ST¹, AF¹ to the dialling trunk GF¹, ST¹ used for the call. The function of stopping the wipers 60 of the trunk connector TC¹ on the proper secondary trunk *st*¹ is performed by identifying circuits *ti*¹, *ti*², which are connected to the banks of the secondary trunks ST that are not multiplied thereat. Each secondary 65 trunk has a separate identifying wire lead-

ing to a contact in the bank of each switch ST. Hence, if there are two secondary trunk finders ST¹, ST² the secondary trunk *st*¹ will have one identifying wire *ti*¹ leading to a contact in the bank of the switch ST¹ and one wire *ti*¹ leading to a contact in the bank of the switch ST². The other secondary trunks as *st*² also each have a separate wire connected to separate contacts in the banks of the switches ST¹, ST². The identifying wires that emanate from the bank of the secondary trunk finder ST² are each connected to one of the contacts of the first vertical row of contacts of each of the trunk connectors TC and the identifying wires that emanate from the bank of the secondary trunk connector ST¹ are each connected to a contact in the second vertical row of each of the trunk connectors TC. Hence, if a potential is applied through an identifying wire that emanates in a secondary trunk finder ST² one contact in the first vertical row of contacts in each trunk connector TC will be connected to battery and if a potential is applied through an identifying wire emanating from the secondary trunk finder ST¹, battery will be connected to one contact in the second vertical row of contacts in each trunk connector TC. It will now be evident that if arrangements are made by which only the first brush or wiper can be connected to the other pole of the battery when the opposite pole has been applied through the secondary trunk finder ST² to a contact in the first vertical row of the bank the particular trunk connector will only be stopped by the identifying circuit when its wipers reach the particular secondary trunk onto which the wipers of the secondary trunk finder ST² have been set. And further if the arrangements are such that the wiper of a trunk connector TC that travels over its second vertical row of contacts can only be connected to the other pole of the battery when the opposite pole has been applied through the secondary trunk finder ST¹ to a contact in the said second vertical row the identifying circuit of the trunk connector can only be closed when its brushes strike the set of contacts connected to the particular secondary trunk onto which the secondary trunk finder ST¹ has been set. The identifying circuit includes a relay 671 (Fig. 3) in the trunk connector and this identifying relay 671 opens the circuit of the operating magnet D when the trunk connector has set its wipers onto the proper secondary trunk. While the trunk connector is thus extending the talking circuit to a wanted line connector WC, Fig. 8 the setting of the wanted line selector WS, Fig. 9, used for the connection proceeds. On the calling subscriber S¹, Fig. 1, sending in his units dialling impulses, these impulses are translated by the

relays AR, Fig. 1, and JR¹, Fig. 9, to the operating magnet EM¹ of the wanted line selector WS¹. The operating magnet EM¹ sets the units designating wiper *u*¹ on to the 5 units designating contact and the wanted line is then designated by the tens designating wiper that was previously set onto the proper tens contact and by the units designating wiper *u*¹. When the first units dialling 10 impulse is sent in a circuit is closed at an off-normal contact *ke* 358 for the operating magnet De¹ of the wanted line connector. This circuit extends through the pair of 15 switches AF¹, ST¹ that has connected the dialling trunk to the secondary talking trunk st¹. The wanted line connector WC¹ is thus set in motion before the unit impulses have all been sent in.

The wanted line connector WC¹ is now 20 caused to set its wipers onto the particular set of contacts of wanted subscriber's line that has been designated by the designating wipers *t*¹ and *u*¹.

If the wanted line is busy by having made 25 a call or by its having been called by another subscriber the test relay in the wanted line connector set onto the contacts of the wanted line S¹ will not be energized and therefore a busy signal circuit will be closed

30 when a slow acting relay V¹ (Fig. 8), energized in the circuit of the operating magnet De¹ of the wanted line connector, allows its armature to drop back. The said busy signal circuit includes a busy relay BR¹ 35 which applies a busy tone from a busy current generator BS_u to one limb of the talking circuit which extends back through the trunk connector TC and calling line connector CC to the calling subscriber S¹.

40 When the slow acting relay V¹ of a wanted line connector WC¹ drops back as described the release magnet ME¹ of the wanted line connector is energized and restores the connector to its normal position. On the calling 45 subscriber replacing his receiver a relay Tc¹ in the calling line connector CC¹ is deenergized and its armature closes an energizing circuit for the restoring magnet M¹ of the trunk connector TC¹ which restores

50 the wipers of this switch to their normal position. The wipers of the calling line connector CC¹ remain upon bank contacts on which they are set.

The release of the switches associated 55 with the dialling trunk is effected independently of whether the wanted subscriber is

60 busy or not by means of a relay 645, Fig. 9 in the wanted line selector WS¹ the moment the wanted line connector WC¹ has been set onto the contacts of the wanted line. The

65 said relay 645 causes the wanted line selector to be restored to its normal position and simultaneously makes the wanted line identifier WJ available for another call. It also releases the group selector finder GF¹ by

causing the circuit of the relay S of this 70 finder to be opened. The deenergization of the relay S is accompanied by the deenergization of the particular test relay, as T¹, of the finder GF¹ and of the relay U¹ of the group selector GS¹, the latter being restored to its normal position by its release magnet M¹ while the brushes of the finder GF¹ remain in a position that they occupy at that moment. The relay U¹ in the group selector 75 that causes this selector to be restored when its armature falls back also opens the circuit of the relays S¹ and T¹ of the calling line finder CF¹ and thus makes this finder available for a new call. It will be remembered that the calling line identifier CJ was made available for a new call as soon as a calling line connector, as CC¹ was set onto the calling line. When this happened a 80 relay Pe¹ in the calling line connector and also a relay P¹ in the calling line finder CF¹ were energized and the latter open the circuit of the relay J¹ of the calling line finder CF¹ and the circuit of the relay Tc in the identifier JC and thus made the identifier 85 ready to respond to a new call.

If the wanted line is free at the moment when the brushes of the wanted line selector WC¹ are set onto its contacts the test relay Pe¹ in the connector WC¹ is energized and locked in the energized position. The locking circuit of the relay Pe¹ and also the energizing circuits of the talking-circuit-extending-relay HR¹ in the trunk connector TC¹ 95 and of the relay Te¹ in the wanted line connector WC¹ are controlled by the relay Tc¹ in the calling line connector CC¹ and the circuit of the relay Te¹ is controlled by the calling subscriber.

The relay Pe¹ on energizing connects the 100 ringing generator RQ to the talking circuit that extends to the wanted station S¹ and ringing currents are then projected periodically through the condenser Ca and the timing switch SS which closes the ringing circuit every ten seconds. On the slow acting relay V¹ allowing its armature to drop back after the relay Pe¹ of the connector WC¹ has been energized the circuits of release

105 magnet Me¹ and the busy relay BR¹ of WC¹ 110 are not closed but a relay FR¹, Fig. 8, is energized which causes a free signal generator FS_u to be connected to the talking circuit so that the calling subscriber receives 115 a signal which indicates that the wanted subscriber is free.

When the wanted subscriber raises his receiver a relay 656 in the wanted line connector WC¹ whose high resistance winding 120 is connected to one limb of the talking circuit is energized. This relay 656 is adapted to attract its armature quicker than the line relay AR¹, Fig. 8, associated with the wanted subscriber's line. The relay 656 immediately closes the circuit of a relay 125 130

in the wanted line connector WC^1 and this latter relay closes thereupon a locking circuit for itself which depends on the calling subscriber and is thus kept closed like the circuit of the relay Pe^1 until the conversation is finished. The said relay 658 keeps the circuit of the relay 656 open. The relay 658 disconnects the ringing generator from the talking circuit and connects a release relay MR^1 in the connector WC^1 to the test wire belonging to the called subscriber's line. The talking connection between the calling subscriber S^1 is now extended through a calling line connector CC^1 , a trunk connector TC^1 and a wanted line connector WC^1 . When the called subscriber replaces his receiver at the end of the conversation his line relay AR' is de-energized and opens the circuit of the associated auxiliary relay TR' . The latter relay is then included in a circuit which extends to the relay MR^1 of the wanted line connector WC^1 and the relay MR^1 then closes a locking circuit for itself controlled by the relay Te^1 and thus depending on the calling subscriber as already described. When the relay MR^1 is energized it closes a circuit through the release magnet Me^1 so that the wanted line connector WC^1 is restored to its normal position.

When the calling subscriber S^1 replaces his receiver his line relay AR is deenergized and also the associated auxiliary relay TR . The latter opens the circuit of the relay Te^1 of the calling line connector CC^1 so that this connector is made available for a new call without its wipers being moved. When the relay Te^1 drops back it causes the circuit of the release magnet M^1 of the trunk connector TC^1 to be closed so that this connector is restored to normal. The relay Te^1 on deenergizing also causes the circuit of the relay Te^1 of the wanted line connector WC^1 to be opened and this latter relay then opens the locking circuits of the relay 658 and Pe^1 . The connection is now completely released and the switches and talking circuits used for the same are now available for other connections.

In the preceding paragraphs the operations involved in establishing a talking connection between two subscribers of one and the same 100 group were outlined. The functions performed in connecting subscribers of different 100 groups are analogous. When a connection is to be established with another 100 group the wipers of the group selector GS , Fig. 4, controlled by the calling subscriber are moved onto a set of contacts connected to the group selector finders GF of the wanted different 100 group. A wanted line selector in the wanted subscriber's group is then set by dialling impulses sent, through the group selector

of the calling subscriber's group and a group selector finder of the wanted subscriber's group. The wanted line selector in the wanted subscriber's group is then set so that its tens and units designating wipers designate the wanted line and a wanted line connector in the wanted subscriber's group is then set onto the wanted line. The talking connection is extended to the wanted line connector through a trunk connector TC in the calling subscriber's group.

The wiring between the various 100 groups is illustrated in Figs. 4, 5 and 7.

Each of the ten sets of contacts (only three shown) in the bank of the first group selector GS^1 of the first 100 group leads to a first set of contacts in the banks of the ten different groups of group selector finders. Thus, the first set of contacts in the bank of GS^1 is connected to the first set of contacts in the bank of the group selector finder GF^1 and to the first set of contacts in the bank of GF^2 of the first 100 group. The second set of contacts in the bank of GS^1 of the first 100 group are connected to the first set of contacts in the bank of each group selector finder in the second 100 group (not shown) and so on. The first set of contacts in the bank of the second group selector GS^2 of the first 100 group is connected to the eleventh set of contacts (fourth set in the diagram, Fig. 7) in each of the banks of the group selector finders GF^1, GF^2 of the first 100 group. The second set of contacts in the bank of GS^2 of the first 100 group is connected to the eleventh set of contacts in each of the banks of the group selector finders (not shown) of the second 100 group and so on.

The banks of the group selectors of the second 100 group II and of the group selectors of the third 100 group III, Fig. 5, are connected to the group selector finders GF in an analogous manner. Thus, the first set of contacts in the bank of GS^1 of the second group II is connected by a bundle of wires 706 to the second set of contacts in each of the banks of the group selector finders GF^1, GF^2 of the first 100 group, Fig. 7. The second set of contacts in the bank of GF^1 is connected by a bundle of wires 707 to the second set of contacts in each of the banks of the group selector finders in the second 100 group, and a third set of contacts in the bank of the group selector GS^1 of the second 100 group II is connected by a bundle of wires 708 to the second set of contacts in each of the banks of the group selector finders in the third 100 group and so on. The first set of contacts in the bank of the group connector GS^2 of the second 100 group is connected by a bundle of wires 709 to the twelfth set of contacts in each of the banks of the group selector finders GF^1, GF^2 of the first 100 group, the second set of contacts in the bank of the group connector GS^2 of the second 100 group is connected by a bundle of wires 710 to the twelfth set of contacts in each of the banks of the group selector finders GF^1, GF^2 of the first 100 group, and so on.

tacts in the banks of the group selector GS² of the second 100 group II is connected by a bundle of wires 710 to the twelfth set of contacts in each of the banks of the group selector finders in the second 100 group and the third set of contacts in the bank of the group selector GS² of the second 100 group is connected to the twelfth set of contacts in each of the banks of the group selector 5 finders in the third 100 group and so on.

The sets of contacts in the banks of the group selectors in the third 100 group III also each lead to sets of bank contacts in group selector finders in different 100 groups 10 in an analogous manner.

The system illustrated in the drawing also includes arrangements by which calling subscribers receive a signal in case all the switches in the dialling trunks or in the talking trunks are engaged. This signal intimates to the calling subscriber that he should not send any dialling impulses before the busy signal ceases, i. e. until switches are 20 available for his call. The circuits by which this signal is given will be hereinafter more fully described.

The novel system also provides means by which all the dialling circuits are immediately released when a calling subscriber abandons his call. If only a calling line finder CF should happen to have been engaged the relays T and S in this finder will be deenergized and this suffices to restore or release the finder CF. If in addition to a calling line 30 finder CF the group selector GS belonging thereto has also been partly or completely set at the moment the call is abandoned the relay S of the calling line finder CF which deenergizes when the calling subscriber replaces his receiver also effects the release of any other seized switches CJ, GS, PT, CC, 40 TC. The relay S of the calling line finder CF will, in such cases, also cause the release of any other switches that have been taken into use, such as AF and ST and WC. If the tens dialling impulses should have been sent in at the moment the calling subscriber abandons the call the deenergization of the relay S of the finder CF will also cause the 50 wanted line identifier WJ to be restored, and if the units impulses should have commenced coming in the wanted line connector WC will also be restored.

The circuits and operations involved in establishing a talking connection between two subscribers will now be described in detail.

When the calling subscriber S¹ raises his receiver the line relay AR is energized by a current flowing over the calling line. The 60 relay AR closes at its contacts 2 a circuit which extends from the positive pole to a winding of the auxiliary relay TR, 3, contacts 2, 1, resistance ψ to the negative pole. The marginal relay TR is partly energized 65 to close its contact 6 and establish a circuit

from the positive pole to the battery through contacts 5, 6, wires 7, 8 which is common to the calling subscriber's group and then is parallel through wires 9, 11, operating magnet D¹, D², contacts 10, 12, interrupter 70

Ub to the negative pole. The operating magnets of the idle calling line finders CF¹, CF² are thus all energized. The sets of wipers of the calling line finders are thus caused to travel simultaneously over different groups of bank contacts. As soon as one 75

of the wipers connected to a test relay T¹, T² or T³, say the wiper 19 of a calling line finder CF¹ strikes the contact, as 18 connected to the wire 16 of the calling line a circuit is closed which extends from the positive pole through the winding 13 of the auxiliary relay, 14, contact 15 of the energized line relay AR, wires 16, 17, Fig. 2, bank contact 18 of the calling line finder CF¹, wiper 19, wire 80

20, low resistance winding 21 of the test relay T¹, back contact 22 of this relay, high resistance winding 23 of the test relay T¹, wire 24, contact 25, high resistance winding 26 and low resistance winding 27 of a common relay S¹, wires 28, 29, 30, off-normal contact 4 85

of the group selector GS¹ to the negative pole. The relays T¹ and S¹ in this circuit are energized. The former short-circuits its high resistance winding 23 by means 90

of its contact 631 and thus applies a busy potential to the wire 16 onto which the wiper 19 has been set. The relay T¹ also opens its contact 632 and thus cuts off the battery from the 95

the energizing winding of the other test relays T² and T³ of the same calling line finder CF¹. The relay S¹ by means of its contact 150 short-circuits its high resistance winding 26 and at its contact 5 it opens the common 100 battery lead to the relays T¹, T² and T³. 105

When the relay S¹ is energized it also opens the circuit of the operating magnet DF¹ at 10 so as to stop the movement of the wipers of CF¹. The relay S¹ also closes its contacts 544, 201, 154 and opens a contact 580 for 110 reasons which will be hereinafter described.

When the relay T¹ shorts circuits its high resistance winding the current flowing through the winding 13 of the auxiliary relay TR is increased sufficiently to cause the auxiliary relay to be completely energized. It then opens its contacts 1 and 5 and closes 115 its contacts 32 and 33. By the opening of contact 5 the circuit extending from the positive pole through 7, 8 to the various driving magnets of the calling line finders is opened so that all the other finders besides CF¹ are stopped. By the contact 33 the negative pole of the battery is connected to a wire 34 and also to the winding 4 of the auxiliary relay TR which latter now keeps the relay TR fully energized.

Where the relay T¹ in the calling line finder was energized it also closed the contacts 43 and 120 125

142. The former connected the stepping 120

magnet HM¹ of the group selector GS¹, Fig. 4, to the dialling wire leading to the relay AR of the calling subscriber and the contact 142 prepared an identifying circuit that includes the identifying relay P¹, Fig. 2.

The calling subscriber S¹ now sends in his 100 dialling impulses which are translated to the stopping magnet HM¹ of the group selector GS¹ so that the wipers of the group selector are stepped onto the set of bank contacts that lead to the wanted 100 group which in this case will be assumed to be the group of the calling subscriber. At each 100 dialling impulse sent in by the calling subscriber S¹ the armatures of the relay AR drop back to close a contact 37 and open a contact 15. The current flowing through the windings of the auxiliary relay TR will thus be intermittently interrupted, but as the relay TR is slow-acting it will keep its armatures pulled up.

When the contact 37 is closed as described by the first 100 dialling impulse a circuit is completed which extends from the off-normal contact k 31, Fig. 4, wires 30, 29, 28, Fig. 2, winding 27, contact 150 of relay S¹, contact 631, winding 21 of relay T¹, wire 20, wiper 19, bank contact 18 of the calling line finder CF¹, wires 17, 16, Fig. 1, 37 of relay AR, wire 38, Fig. 2, wire 39, bank contact 40, wiper 41, wire 42, contact 43 of relay T¹, wires 44, 45, Fig. 4, contact 46 of relay U¹ in the group selector GS¹, wires 47, 48, Fig. 2, energizing winding 49 of the slow-acting relay V¹, wire 50 and then partly through the wire 51, Fig. 4, to the stepping magnet HM¹ of the group selector and to the positive pole of the battery, and partly through the wires 52, 53, Fig. 1, wiper 54 that will be assumed to have been set onto the primary trunk PT¹, wires 56, 57, 58, Fig. 3, stepping magnet Dg¹ of the group marking switch GS¹ in the trunk connector TC¹ to the positive pole of the battery. It is thus seen that the 100 dialling impulses cause the wipers of the group selector GS¹ in a dialling trunk and the wiper of a group marking switch GS¹ associated with a talking trunk connector TC¹ to be set simultaneously, the wipers of the group selector GS¹ being set onto a set of bank contacts that lead to group selector finders GF in the wanted group, and the wiper of the group marking switch GS¹ being set onto a contact which marks a group of bank contacts in the bank of the trunk connector TC¹. The relays T¹ and S¹ are slow-acting like the relay TR so that they keep their armatures attracted during the interruptions between the dialling impulse. The first 100 dialling impulses sent in causes the slow-acting relay V¹ to be energized and this relay keeps its armature attracted until shortly after all the 100 dialling impulses

have been sent in. It keeps the dialling impulse circuit closed at its contact 60 so that when the off-normal contact k 31, Fig. 4, is opened at the first step executed by the group selector GS¹ the dialling circuit is maintained closed.

Let it be assumed that the number of 100 dialling impulses sent in is l so that the wipers of the group selector GS¹ and the wiper of the group marking switch GS¹ are each caused to execute one step.

When the relay V¹ is energized it closes a circuit at its contact 61 which extends from the positive pole of the battery through a contact 62 of a relay J¹, second winding 63 of the relay V¹, wires 64, 65, contact 66, stepping magnet Dc of the calling line identifier CJ, interrupter Uw to the negative pole of the battery. The stepping magnet Dc and the winding 63 of the slow-acting relay V¹ are thus energized and the magnet Dc steps the wipers of CJ round until they strike upon the particular dialling trunk to which the calling line finder CF¹ belongs. The winding 63 of the relay V¹ will maintain the circuit of the stepping magnet Dc closed even if the 100 dialling impulses should cease before the calling line identifier CJ has been set onto the dialling trunk used. The winding 49 of the slow-acting relay V¹ thus only serves to indicate the closure of the circuit of Dc when the 100 impulses commence coming in.

When the wiper 70 of the calling line identifier strikes a bank contact that leads to the dialling trunk used for the call a circuit is closed which extends from the positive pole of the battery through contacts 61 and 62, wire 67, relay J¹, wire 68, bank contact 69, wiper 70, relay Te to the negative pole of the battery. The relays J¹ and Te in this circuit are energized, the latter opening the circuit of the driving magnet Dc at its contacts 66 and thus stopping the wipers of the calling line identifier and the relay J¹ closing a part which leads from the positive pole of the battery through 71, 72, 73, Fig. 1, wiper 78 of the primary trunk finder PT¹, bank contact 79, wires 80, 81, bank contact 82 of the primary trunk finder PT². If the wipers of the primary trunk finder PT² should be standing on the set of bank contacts to which 82 belongs, or in other words, if the primary trunk finder PT² should have been set onto the same primary trunk as PT¹ the current path just traced would extend through the wiper 83, relay Ep² of PT², wire 84, Fig. 2, wires 85, 86, 87, 88, Fig. 4, off-normal contact k 89 which is closed as long as the group selector GS² is in its normal position, to the negative pole. The relay Ep² is thus energized and at its contact 90 it closes the circuit of the driving magnet Dp² on the primary trunk finder PC². This circuit extends from the negative pole of the

battery to the interrupter U_b , contact 91 of the relay S_p , Fig. 2, wires 92, 93, 94, D_p^2 , contact 90, wire 95, Fig. 2, wires 96, 97, contact 98 of the relay J^2 to the positive pole. The driving magnet D_p^2 is thus caused to move the wipers of the trunk finder PT^2 away from the bank contacts of the trunk seized by the trunk finder PT^1 and the movement of the wipers PT^2 continues until they reach a disengaged trunk, i. e. a trunk whose contact that corresponds to 424 of HR^1 , Fig. 3, in the trunk connector TC in which it terminates is not closed.

The closure of the contact 71 of the relay J^1 also results in the completion of the following circuit: Positive pole of the battery 71, Fig. 2, 72, 73, wiper 78, bank contact 79, wires 80, 99, 100, Fig. 3, contact 101 of relay HR^1 in the trunk connector TC^1 , wires 102, 103, 104, relay F^1 , to the negative pole. The relay F^1 is energized and prepares a circuit for the relay Pc^1 at the contact 129. At its contact 118 the relay F^1 also closes the circuit of the driving magnet Dc^1 of the calling line connector CC^1 which extends from the positive pole through 118, 119, 120, 121, Dc^1 , U_b to the negative pole. The driving magnet Dc^1 now causes the wipers of the calling line connector to be stepped onto the set of bank contacts that leads to the particular calling subscriber S^1 whose call was extended through the calling line finder CF^1 and through the primary trunk finder PT^1 to the primary trunk Pt^1 to which the calling line connector CC^1 belongs. When the wipers of CC^1 reach the said calling subscriber's line a circuit is closed which extends from the positive pole through the wire 123 of the calling line identifier, Fig. 2, wires 126, 127, wiper 128, bank contact 129 of the primary trunk finder PT^1 , wires 130, 131, contact 122, relay Pc^1 , wire 134, wiper 135, bank contact 136 of the calling line connector CC^1 , wires 137, 138, Fig. 2, bank contact 139, wiper 140, wire 141, contact 142, wire 143. Relay P^1 , Fig. 2, bank contact 145 wiper 146 of the calling line identifier CJ to the negative pole. The relays P^1 , Fig. 2 and Pc^1 of the calling line connector CC^1 , Fig. 1, are energized. The latter relay opens at its contact 121 the circuit of the driving magnet Dc^1 and stops the wipers of CC^1 on the calling line. At its contact 148 the relay Pc^1 closes an energizing circuit for the relay Te^1 which extends from the positive pole through the contact 148, relay Te^1 , wiper 149, bank contacts 36 of CC^1 , wires 35, 34, contacts 32, 33 of the auxiliary relay TR to the negative pole. The relay Te^1 on energizing closes a locking circuit for itself which extends through 454 and keeps itself energized independently of the contact 148 Pc^1 and also maintains the circuit of the driving magnet Dc^1 open after the relay Pc^1 is deenergized and closes

its contact 121. At its contacts 318 the relay Te^1 also connects the positive pole to the wire 317 by which operations are started that will be described later.

The relay P^1 , Fig. 2, that is energized at the same time as Pc^1 opens at its contact 152 the locking circuit that the relay J^1 had closed for itself and that extends through 151, 152, 153, 154 to the positive pole. The relay J^1 and also the relay Te in the calling line identifier CJ are thus simultaneously deenergized and the identifier CJ then immediately becomes available for other calls.

The slow acting relay V^1 which was energized together with the stepping magnet HM^1 of the group selector GS^1 , Fig. 4, and the stepping magnet Dg^1 of the group marking switch GS^1 , Fig. 3 closes the circuit of a slow acting relay W^1 in the group selector GS^1 . When the armature of the relay V^1 drops back after the relay W^1 has been energized a circuit is closed that extends from the positive pole of the battery through relay W^1 , wires 157, 156, contact 159 of the deenergized relay V^1 , wire 160, contact 161 of the relay W^1 , contact 162 of the relay U^1 , wire 163, wiper 164, bank contact 165 of the group selector GS^1 , wires 166, 167, 168, Fig. 7 and then partly through wire 169, stepping magnet D of the group selecting finder GF^1 , contact 170 to the negative pole, and partly through 171, 172, driving magnet D' of the group selector finder GF^1 , contact 173, interrupter U_b to the negative pole. The two driving magnets D and D' and the relay W^1 thus receive current impulses by which the wipers of the group selector finders GF^1 and GF^2 are caused to travel over their bank contacts until a hunting wiper strikes the dialling trunk onto which the group selector GS^1 has been set. The said impulses also keep the slow-acting relay W^1 energized. When a hunting wiper of a group selector finder, say GF^1 reaches the dialling trunk onto which the group selector GS^1 has been set a circuit is completed which extends from the positive pole of the battery, relay W^1 , Fig. 4, wires 157, 156, Fig. 2, contact 159 of relay V^1 , wire 160, contact 174 of W^1 , wire 175, relay U^1 , wire 176, wiper 177, bank contact 178, wires 179, 180, Fig. 7, bank contact 181, wire 183, low resistance winding 184, contact 185, high resistance winding 186 of the relay T^1 of the group selector finder GF^1 , wire 187, contact 188, high resistance winding 189 and low resistance winding 190 of the relay S , wires 191, 192, Fig. 9, 193, contact 194 of the release magnet M of the wanted line selector or designating switch WS^1 to the negative pole of the battery. The current flowing in this circuit energizes the relays U^1 of the group selector GS^1 and T^1 and S of the group selector finder GF^1 . The relay U^1 at its contact 46 disconnects the driving mag-

nets HM¹ of the group selector GS¹ and Dg¹ of the group marking switch GS¹ from the dialling wire 45 and connects this wire through contact 202 to the dialling wire 203 that leads through the group selector and group selector finder to the impulse relay JR¹ of the designating switch WS¹, Fig. 9.

The relay T¹, Fig. 7, of the group selector finder GF¹ on energizing shortcircuits its high resistance winding 186 by means of its contact 196 and the relay S shortcircuits its windings 189 by its contact 195. By this means the dialling trunk picked up by the group selector finder GF¹ is rendered busy and unseizable by any other group selector finder GF and by the opening of the contacts 188 and 578 of the relays S and T¹ respectively the relay T² is prevented from connecting the second calling dialling trunk through to the designating switch WS. The action of the relays T and S of GF¹ in this respect is similar to that described above in connection with the relays T and S of the calling line finder CF¹, Fig. 2. The relay S of the finder GF¹ on energizing closes at its contact 213 a circuit that extends from the positive pole through 213, wire 214, Fig. 6, contact 215 of relay C¹, wire 216, relay R¹, contact 217 of relay T¹ to the negative pole. The relay R¹ in this circuit is energized and opens at its contact 222 the lead to the relay R² and thus prevents the wipers of the finders AF² and ST² from being moved. At its contact 218 the relay R¹ closes an energizing circuit for the driving magnet D¹ this circuit extending from the negative pole through the interrupter Ub contact 221, wire 220, DF¹, 229, 228, 216, 215, 214, 213 to the positive pole. The driving magnet D¹ moves the wipers of the auxiliary finder AF¹ until they strike the set of bank contacts that leads to the dialling trunk corresponding to the group selector finder GF¹, Fig. 7. A circuit is then closed which extends from the positive pole through contact 230 of the relay S of finder GF¹, Fig. 7, wire 229, Fig. 6, relay O¹, wire 228, contact 227, wiper 226 of the dialling trunk finder or auxiliary finder AF¹, windings 225, 224 of the relay T¹, contact 223 of relay R¹ to the negative pole. By this circuit the relay O¹ and also the relay T¹ are energized. The latter shortcircuits its high resistance windings 224 by its contact 231 and thus renders the dialling trunk GF¹ unseizable by other dialling trunk finders. At its contact 219 the relay T¹ opens the circuit of the driving magnet D¹ and at its contact 217 it opens the circuit of the relay R¹. At its contact 232 the relay C¹ closes an energizing circuit for a relay Ps¹ while opening a contact 588. By this means the secondary trunk finder ST¹ which has been previously set onto an idle secondary trunk has its wipers kept standing on this trunk but any other finder such as ST² whose

wipers may have been set onto the same trunk has its driving magnet Ds² energized in the manner described in connection with the primary trunk finder PT¹. The secondary trunk finder ST² would then be set in motion and caused to set its wipers onto some disengaged secondary trunk. 70

The relay T¹ keeps the circuit of the driving magnet Ds¹ of the secondary trunk finder ST¹ open at the contact 588 so that the driving magnet Ds¹ is prevented from moving the wipers of the secondary trunk finder ST¹. At its contact 232 the relay T¹ also closes the circuit which extends from the positive pole through contact 232, wire 234, wiper 235, bank contact 236 of the secondary trunk finder ST², wires 240, 241, relay Ps² to the negative pole of the battery. The relay Ps² is thus energized and causes the driving magnet Ds² to drive the wipers of the finder ST² forward until they reach a free secondary trunk. As long as the wipers keep striking busy trunks the relay Ts² receives energized currents through off-normal contacts corresponding to the contact ke 246 of the wanted line connector WC¹, Fig. 8. 80

The relay O¹ on energizing opens its contact 215 and thus also keeps the circuit of the relay R¹ open. At its contact 247 the relay O¹ closes the following circuits: Positive pole of the battery, 247, 248, Fig. 7, 249 of T¹, wiper 250, bank contact 251 of the group selector finder GF¹, wire 252, Fig. 4, wire 253, bank contact 254, wiper 255 of group selector GS¹, wire 256, contact 257 of the energized relay U¹, wire 258, Fig. 2, wire 259 and 260, Fig. 1, wiper 261, bank contact 262 of the primary trunk finder PT¹, wires 263, 264, relay R¹, Fig. 1, wire 265, Fig. 3, contact 266 of the relay HR¹ of the trunk connector TC¹ to the negative pole. By this circuit the relay R¹, Fig. 1, is energized and closes at its contact 267 a circuit which extends from the negative pole of the battery through the interrupter Ub, contact 267, wire 268, Fig. 3, driving magnet D¹ of the trunk connector TC¹, contact 269 of the identifying relay 671, contact 270 of relay HR¹ to the positive pole. The driving magnet D¹ in this circuit is then energized periodically and drives the wipers of the trunk finder TC¹ over their bank contacts until they strike the particular set of bank contacts that leads to the secondary trunk onto which the wipers of the secondary trunk finder ST¹, Fig. 6, that is being used for the call have been set. Before the wipers of the trunk connector TC¹, Fig. 3 reach this particular secondary trunk a preliminary group selecting function which has been prepared by the group marking switch GS¹ takes place. By this group selecting function the wipers of the trunk connector TC¹ are moved to the group of 125 130 135 140 145 150 155 160 165 170 175 180 185 190 195 200 205 210 215 220 225 230 235 240 245 250 bank contacts that is connected to the secondary trunks which lead to the selected 100 group. When the wiper 274 strikes the contact 275 which was previously connected to the positive pole by the wiper 278 of the group marking switch GS¹ (which was set by the 100 dialling impulses) a circuit is closed which extends from the negative pole of the battery through contact 271 of the relay HR¹, relay 674, contact 272 of this relay, wire 273, wiper 274, group marking contact 275 of the trunk connector TC¹, wire 276, bank contact 277, wiper 278 of the group marking switch to the positive pole. The relay 674 in this circuit is energized and closes a locking circuit for itself at its contact 279 which is independent of the wiper 274. The relay 674 on energizing prepares identifying circuits at its contacts 589 and 301. These identifying circuits include the two windings of the identifying relay 671. The particular identifying circuit or winding of the relay 671 that will receive current will depend on whether the secondary trunk 25 onto which the wipers of the trunk connector TC¹ are to be set has been seized by the secondary trunk finder ST¹ or ST². It has been assumed that this secondary trunk has been seized by the secondary trunk finder ST¹ and hence the identifying circuit or winding of the identifying relay 671 will be the upper winding of 671 as will presently appear.

When the wipers of the trunk connector TC¹ reach the secondary trunk that has been seized by the secondary trunk finder ST¹ used for the call a circuit will be completed which extends from the positive pole through the contact 280 of the relay Ps¹, Fig. 6, wire 281, wiper 282, bank contact 283, wire 284, Fig. 7, winding 285 of relay X, Fig. 7, wires 268, 287, contact 288 of the energized test relay T¹, bank contact 290 of the group selector finder GF¹, wire 291, Fig. 4, bank contact 292, wiper 293 of the group selector GS¹, wires 294, 295, Fig. 2, 296, Fig. 1, wiper 297, bank contact 298, wires 299, 300, Fig. 1, contact 301, lower winding of relay 671, wiper 304, bank contact 305, wire 306, identifying wires 307, 308, Fig. 6, 309, bank contact 310, wiper 311, wire 312, contact 313 of the relay Ps¹ to the negative pole. The identifying relay 671 in this circuit is energized and at its contact 314, Fig. 3, it closes the circuit of the relay HR¹ as follows: Negative pole of the battery, contact 314, wire 315, relay HR¹, wire 316, Fig. 1, wire 317, contact 318 of the relay Tc¹ at the calling line connector CC¹ to the positive pole. The relay HR¹ is thus energized and locks itself to the negative pole of the battery by its contact 319, this locking circuit remaining closed until the relay Tc¹ is de-energized at the end of the conversation. The relay HR¹ also opens the circuit of the

driving magnet D¹ at the contact 270. This circuit had, however, been already opened at the contact 269 of the relay 671. At its contact 266 the relay HR also opens the circuit of the relay R¹, Fig. 1 and at its contact 271 the relay HR¹ opens the circuit of the relay 674 which in turn opens the identifying circuits through 671 at the contacts 301 and 589. At its contact 101 the relay HR¹ opens the circuit of the relay F¹, Fig. 1, and by its contact 424 the relay HR¹ applies the positive pole of the battery to the wire 100 which extends to the wire 99, Fig. 1, and hereby the primary trunk belonging to the trunk connector TC¹ is made unseizable to any primary trunk finders that may be in the act of those hunting for a free trunk.

The current in the above mentioned identifying circuit in addition to energizing the identifying relay 671 in the trunk connector TC¹, Fig. 3, also energized the relay X, Fig. 7, by means of its upper winding 285. The relay X then closed a contact 615 and prepared an energizing circuit for the release magnet M¹ of the designating switch WS¹, Fig. 9. This circuit is, however, kept open until the wanted line connector WC¹ has connected the secondary trunk used for the connection to the wanted line. The release of the dialling trunk that terminates in the designating switch WS¹ is thus delayed until the trunk connector has extended the primary trunk to the secondary trunk. It may, however, happen, that the trunk connector extends the connection to a secondary trunk before the wanted line connector WC extends the secondary trunk to the wanted line.

The relay HR¹ of the trunk connector TC¹, Fig. 3, extends the primary trunk to the secondary trunk by closing its contact 321 and 322 and at the same time it closes a circuit through its contact 464 which extends from the positive pole through 464, wire 463, wiper 462, bank contact 461, wires 460, 459, Fig. 6, wire 458, Fig. 8, wire 457, relay Te¹, wire 456, off-normal contact 455 which is closed at the first step of the wanted line connector whose wipers may now have been set onto the wanted line in the manner to be hereinafter described, to the negative pole of the battery. The relay Te¹ in this circuit is energized and prepares circuits at its contacts 465 and 482 which will be more fully described later.

The tens dialling impulses sent in by the calling subscriber S¹ are translated by the impulse relay JR¹, Fig. 9, into the tens driving magnet ZM¹ of the line designating switch WS¹ and the said magnet sets the tens designating wiper t¹ onto a bank contact, say 349, by which the particular tens group to which the wanted subscriber belongs is designated. The energizing circuit

of the tens driving magnet ZM^1 extends from the negative of the battery through contact 324 of the impulse relay JR^1 , wires 325, 326, contact 327 of the relay ST^1 , Fig. 9, wires 328, 329, winding 330 of the slow-acting relay Vz^1 , wires 331, 332, tens magnet ZM^1 to the positive pole. It is thus seen that the relay Vz^1 is energized together with the tens driving magnet. The relay Vz^1 on energizing closes a circuit at its contact 333 which extends from the positive pole of the battery through the contacts 333, 334 of relay J^1 of the line designating switch WS^1 , wire 335, winding 336 of the relay Vz^1 , wires 337, 338, contact 339 of the relay Ti in the wanted line identifier WJ , driving magnet Di of the identifier, interrupter Ub , to the negative pole. The driving magnet Di and the relay Vz^1 in this circuit are intermittently energized and as the relay Vz^1 is slow acting it will keep its armature attracted even if the tens impulses that flow through its winding 330 momentarily cease. The driving magnet Di sets the wipers of the wanted line identifier WJ onto the dialling trunk which terminates in the line designating switch WS^1 . When this trunk is reached by the wipers of the identifier a current flows from the negative pole of the battery through the relay Ti of the identifier, wiper 342, bank contact 341, wire 340, relay J^1 of the switch WS^1 , contact 334, contact 333 of the slow-acting relay Vz^1 to the positive pole. The relay J^1 in this circuit is energized and closes a locking circuit for itself which is independent of the relay Vz^1 , this locking circuit extending from the negative of the battery through the relay Ti , wiper 342, bank contact 341, wire 340, relay J^1 , contact 343 of the same, wire 344, contact 345 of the relay 645, wires 346, 347, Fig. 7, contact 348 of the relay S of the group selector finder GF^1 to the positive pole.

The relay Ti in the wanted line identifier WJ is energized at the same time as the relay J^1 of the designating switch WS^1 , and at its contact 339 it opens the circuit of this driving magnet Di and thus stops the motion of the wipers of WJ .

When the tens dialling impulses have all been sent in and the wipers of the identifier WJ have been set onto the dialling trunk used for the call the relay Vz^1 lets its armature drop back and the relay ST^1 of the designating switch WS^1 is then included in a circuit which extends from the positive pole of the battery through the off-normal contact 350 closed when the designating switch WS^1 executes its first step, wire 351, relay ST^1 , wires 352, 353, contact 354 of the relay Vz^1 to the negative pole. The relay ST^1 then disconnects at its contact 327 the tens driving magnet ZM^1 from the impulse wire that leads from the impulse relay JR^1 and connects this impulse wire through the contact

355 to the units driving magnet EM^1 of the designating switch WS^1 . The units dialling impulses now sent by the calling subscriber now flow through the wire 356 and through the units driving magnet EM^1 which sets the units designating wiper u^1 of the designating switch WS^1 onto a units designating contact, such as 357 which designates the particular line in the previously designated tens group wanted by the calling subscriber. 75

When the units designating wiper of the switch WS^1 executes its first step the off-normal contact 358 is closed to complete the following circuits: Positive pole of the battery, contact 358, wire 359, contact 360, wire 361, Fig. 8, wires 362, 363, Fig. 6, wires 364, 365, contact 366 and wiper 367 of the dialling trunk finder AF^1 , wire 368, wiper 369 and bank contact 370 of the secondary trunk finder ST^1 , wires 371, 372, 373, Fig. 8, wires 374, 375, slow-acting relay V^1 of the wanted line connector WC^1 , driving magnet De^1 , interrupter Ub to the negative of the battery. The relay V^1 and driving magnet De^1 in this circuit are energized intermittently, the driving magnet De^1 stepping the wipers onto the set of bank contacts designated by the designating switch and the relay V^1 keeping its armature attracted until the wipers of the wanted line connector WC^1 are stopped. As soon as the wiper 396 of the wanted line connector WC^1 strikes the group designating contacts 397 a circuit is closed which extends from the negative pole of the battery to the wiper 376, the bank contact 377 of the wanted line identifier WJ , Fig. 9, wires 378, 379, winding 380 of the relay 645, winding 381 of the relay 643, wire 382, Fig. 8, wires 383, 384, Fig. 6 wires 385, 386, bank contact 387 and wiper 388 of the dialling trunk finder AF^1 , wire 389, wiper 390, bank contact 391 of the secondary trunk finder ST^1 , wires 392, 393, Fig. 8, wires 394, 395, wiper 396, group designating contact 397, wire 398, 399, 400, Fig. 9, wire 401, tens designating contact 349 in the designating switch, tens designating wiper t^1 of the designating switch WS^1 resistance 402, contact 403 of the relay 643, wire 404, 405, 406, bank contact 407 and wiper 408 of the wanted line identifier, to the positive pole of the battery. As the resistance 402 is included in this circuit the relay 643, but not the relay 645 will be energized. The former relay 643 closes a locking circuit for itself which extends from the positive pole of the battery through the winding 409, contact 410, contact 411 of relay 645, wire 412, 413, Fig. 7, contact 414 of the relay S in the group selector finder GF^1 to the negative pole of the battery. The relay 643 is kept energized in this circuit after the wiper 396 is stepped beyond the bank contact 397 of the wanted line conductor WC^1 . At its contact 403 the relay 643 disconnects the wiper t^1 and the resistance 402 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

from the identifying wire 404 and connects the latter through its contact 415 to the wiper u^1 . As soon as the wiper 396 of the wanted line connector WC^1 , which continues 5 moving, strikes the units designating contact 416 a circuit is closed which extends from the negative pole of the battery through 376, 377, Fig. 9, 378, 379, 380, 381, 382, Fig. 8, 383, 384, Fig. 6, 385, 386, 387, 388, 389, 390, 10 391, 392, 393, Fig. 8, 394, 395, wiper 396 of the wanted line connector WC^1 , units designating contact 416 in this connector, wires 417, 418, 419, Fig. 9, wire 420, units designating contact 357 and units designating 15 wiper u^1 of the designating switch WS^1 , wire 421, contact 415 of relay 643, wire 404, 405, 406, contact 407 and wiper 408 of the wanted line identifier WJ to the positive pole of the battery. The relay 645 in this circuit is energized and closes a locking circuit for itself 20 which extends from the positive pole of the battery through winding 422 of 645, contact 423, wire 412, 413, Fig. 7, contact 414 to the negative pole of the battery. At its contact 25 411 the relay 645 opens the circuit of the relay 643. At its contact 525 the relay 645 closes a circuit which extends from the negative pole of the battery through contact 425, wire 427, Fig. 8, wires 427, 428, Fig. 6, wires 30 429, 430, bank contact 431 and wiper 432 of the dialling trunk finder AF^1 , wire 433, wiper 434 and bank contact 435 of the secondary trunk finder ST^1 , wire 437, 438, Fig. 8, wire 439, 440, 441, winding 442 of the test 35 relay Pe^1 , wire 443, wiper 444, bank contact 445 of the wanted line connector WC^1 , wire 446, 447, test wire 448 of the wanted line, contact 449 of the line relay AR^1 , winding 550 of the auxiliary relay TR^1 to the positive pole. 40 This test circuit will be completed only if the desired subscriber S^1 is not engaged, i. e. if the wanted subscriber's relay AR^1 is not energized and the contact 449 of this relay is closed. 45 At its contact 360 the relay 645 also opens the circuit of the driving magnet De^1 and the slow acting relay V^1 of the wanted line connector WC^1 , thus stopping the wipers of the same. The relay V^1 of the connector WC^1 then allows its armatures to drop back. 50 At its contacts 345 the relay 645 also opens the circuit of the relays J^1 and T^1 and thus releases the identifier WJ . At its contact 573 the relay 645 completes a circuit from the negative pole of the battery through contact 573, wire 572, 571, Fig. 7, wire 570, 569, contact 615 of relay X , contact 575 of the relay S of the group selector finder GF^1 , wire 576, Fig. 9, wire 577, release magnet M^1 of the 55 wanted line selector WS^1 and then through the off-normal contacts 579 and 616 to the positive pole of the battery. The release magnet M^1 in this circuit is energized and restores the designating switch WS^1 to normal. When the tens wiper t^1 of this switch 60 reaches its normal position the off-normal contact 660 is opened and the off-normal contact 579 is opened when the units wiper u^1 reaches its normal position and the release magnet M^1 will then be deenergized. 70 When the latter was energized it opened at its contact 194 the circuit of the relays S and T^1 of the group selector finder GF^1 , Fig. 7, and of the relay U^1 of the group selector GS^1 , Fig. 4. The relays S and T^1 75 make the group selector finder GF^1 available for another call without causing its wipers to move. The relay U^1 , Fig. 4, opens at its contact 614 the circuit of the relays S^1 and T^1 of the calling line finder CF^1 , Fig. 2, and therefore also deenergizes the winding 13 of the auxiliary relay TR of the calling line, Fig. 1. The auxiliary relay TR is not immediately deenergized because current continues flowing through its other winding. The relays S^1 and T^1 , however, allow their armatures to drop back and make the calling line finder CF^1 available for new calls without causing its wipers to move. 80 The relay S^1 , Fig. 2, closes at its contact 580 a circuit which extends from the positive pole of the battery through the off-normal contact 583, release magnet M^1 , wire 582, Fig. 2, wire 581, contact 580 of the relay S^1 in the calling line finder CF^1 to the negative pole. The release magnet M^1 in this circuit is energized and restores the group selector GS^1 to normal. When this restoring function is completed the off-normal contact 583 is opened and 77 closed. The former 90 contact opens the circuit of the magnet M^1 and by the latter the circuit of the relay Ep^1 of the primary trunk finder PT^1 , Fig. 1, is closed. The relay Ep^1 is thus energized and closes at its contact 610 the driving magnet Dp^1 which steps the wipers of the primary trunk finder PT^1 off the talking trunk CC^1 — TC^1 and moves then onto an idle trunk. The 95 dialling trunks and switches used temporarily for the call have now been released or made available for another call. 100 It is to be noted that the release of the dialling trunks and temporarily used switches takes place as soon as the wanted line connector has reached the bank contacts of the wanted line independently of the condition of this line, i. e. no matter whether this line is busy or idle. It is also to be mentioned that the time that the identifiers CJ and WJ are appropriated for a connection is 105 reduced to a minimum, the identifier CJ being taken into use only when the hundreds dialling impulses commence coming in and being released immediately after the calling line connector CC used for the call is set 110 onto the calling line, while the identifier WJ is only taken into use when the tens impulses commence coming in and is made available for other connections as soon as a wanted line connector WC used for the con- 115 120 125 130

nection is set onto the wanted line. In order to prevent a calling subscriber from holding the dialling trunks for too long, a time fuse or circuit opener may be placed in the lead 5 of the coil 13 of the auxiliary relay TR which opens the circuit of this coil after a certain time. This will have the effect of releasing the calling line finder CF¹ used for the call so as to make this finder and 10 the dialing trunks accessible through it available for another call.

If, when the wanted line connector WC¹ is set onto the wanted line, this line should be engaged so that the test relay Pe¹ in the connector WC¹ does not energize, a circuit 15 will be closed when the armature of the relay V¹ of WT¹ drops back. This circuit extends from the positive pole of the battery through the off-normal contact 474, release magnet Me¹, wire 473, contact 472 of the relay Pe¹, wire 471, contact 470 of the relay V¹, to the negative pole of the battery. The release magnet Mi¹ in this circuit is 20 energized and restores the wanted line connector WC¹ to its normal position when the off-normal contact 474 will be opened to interrupt the circuit of the release magnet. The relay V¹ on deenergizing when the relay Pe¹ is deenergized closes a circuit through 25 its contact 476 which extends from the positive pole of the battery through the off-normal contact 475, contact 476 of the relay V¹, wire 477, contact 478 of relay Pe¹, wire 479, relay BR¹ to the negative pole of the 30 battery. The relay BR¹ in this circuit is energized and closes at its contact 480 a locking circuit for itself which extends through a contact 482 of the relay Te¹ and which remains closed when the off-normal 35 contact 475 is opened on the connector WC¹ reaching its normal position. At its contact 483 the relay BR¹ connects the busy signal producer BS¹ to one limb of the talking 40 circuit that extends back to the calling subscriber. A busy tone current then flows from the positive pole through the winding 484 of an induction coil, Fig. 8, wire 485, contact 483, wire 487, Fig. 7, wires 488, 489, Fig. 3, wire 607, bank contact 490, wiper 45 496 of the trunk connector TC¹, wire 605, contact 321, wire 604, Fig. 1, wire 603, wiper 490' and bank contact 491 of the calling line connector CC¹, wire 492, 493, winding 598 of the relay AR to the negative pole, and 50 also through the subscriber's station S¹ and through the right winding of the relay AR. The calling subscriber S¹ on hearing this busy signal will replace his receiver and this will cause the calling line connector CC¹ and the trunk connector TC¹ to be restored to normal in the following manner: When the receiver is replaced the line relay AR of the calling subscriber is deenergized and opens at its contact 2 the circuit of the 55 winding 4 of the auxiliary relay TR. This

relay then lets its armature drop back and opens at its contacts 32, 33 the circuit of the relay Te¹ of the calling line connector CC¹ and this relay in turn opens at its contact 318 the circuit of the relay HR, Fig. 6 of the trunk connector TC¹. The calling line connector CC¹ is released and made available for another call without its wipers being moved. The relay HR¹, Fig. 3, closes at its contact 594 the circuit of the released magnet M¹ of the trunk connector TC¹ which 75 restores the wipers of the trunk connector and also the wiper of its group marking switch GS¹ to their normal positions. When these wipers reach their normal position the 80 off-normal contact 589 of the marking switch GS¹ and the off-normal contact 590 of the trunk connector TC¹ are opened to deenergize the released magnet M¹. The relay HR¹ on deenergizing also opens at its contact 464 the circuit of the relay Te¹ at the 85 wanted line connector WC¹, Fig. 8, and the relay Te¹ in turn opens at its contact 482 the circuit of the relay BR¹ which thereupon 90 disconnects the busy tone producer BS¹ from the talking wire.

If, the wanted subscriber is free when the wanted line connector WC¹, Fig. 8, is set onto the wanted line in the manner described, the test relay Pe¹ will be energized by a current through its coil 442. As its contact 617 the test relay Pe¹ will then close a locking circuit including its locking winding 494 and extending from the negative pole of the battery through 494, 617, wire 495, contacts 465 of the relay Te¹ to the positive pole. The relay Pe¹ also closes at its contact 468 a circuit that extends from the negative pole of the battery through the contact 468, wire 467, relay He¹, wire 466, contact 465 to the positive pole. The relay He¹ in this circuit is energized and closes a locking circuit for itself which extends from the negative pole of the battery through the contact 469, He¹, 466, 465 to the positive pole. The relay He¹ prepares at its contact 522 a circuit for the release magnet Me¹ of the wanted line connector WC¹. At its contacts 496 and 497 the relay Pe¹ connects the talking wires 526 and 532 through 100 to the wanted subscriber and a ringing current is then sent to the wanted subscriber. This ringing current flows from the ringing generator RQ, Fig. 8 through a condenser Co, wire 528, relay FR¹, contact 527, wire 526, contact 496, wire 501, wiper 502, bank contact of the wanted line connector WC¹, wire 504, talking wire 505 of the wanted line, wanted subscriber's station S¹, wire 506 of the wanted line, wire 507, bank contact 508, wiper 509 of the wanted line connector WC¹, wire 510, contact 497, wire 532, contact 531, wire 530, 529, interrupter SS back to the 105 ringing current generator RQ. This ringing current produces periodic rings of the 110

subscriber's bell and when the wanted subscriber S^1 responds by raising his receiver the following circuit is closed: Positive pole of the battery, contact 513 of the relay 658, 5 wire 512, contact 511 of the relay Pe^1 , wire 510, wiper 509, bank contact 508 of the wanted line connector WC^1 , wire 507 and 10 506, wanted subscriber S^1 , wire 505, 504, bank contact 503, wiper 502, wire 501, contact 498, relay 656, wire 500, contact 499 of the relay 658 to the negative pole of the battery. The relay 656 in this circuit responds 15 quicker than the line relay AR^1 which is also energized when the wanted subscriber 20 raises his receiver. The relay 656 closes at its contact 514 a circuit which extends from the negative pole of the battery through contact 514, wire 515, 516, relay 658, contact 465 of the relay Te^1 to the positive pole. 25 The relay 658 in this circuit is energized and closes a locking circuit for itself which extends from the negative pole of the battery through contact 517, relay 658, contact 465 to the positive pole of the battery. The relay 658 disconnects at its contacts 527 and 30 531 the ringing current and the relay FR^1 from the wanted subscriber's line and connects this line through to the calling subscriber by its contacts 533 and 534 while opening the circuit of the relay 656 at its contacts 499 and 513. At its contact 519 the relay 658 prepares a circuit for the release relay MR^1 . While ringing current flows to the wanted subscriber S^1 the relay FR^1 is 35 energized periodically and periodically connects a "free signal" producer FSu through the contact 584 to the talking wire 487 and the calling subscriber thus obtains a signal intimating that the wanted line is free 40 and that ringing current is being sent out to the wanted subscriber. On the wanted subscriber raising the receiver the talking connection is completed as previously described.

45 When a connection is established between a calling subscriber in a certain 100 group (or 1,000 group) and a wanted subscriber in a different 100 (or 1,000) group the operations involved are analogous to those described above the only difference being that the group selector finder GF , designating switch WS and wanted line connector WC used for the connection will be in the group of the wanted subscriber. The trunk connector T will be in the group of the calling subscriber.

50 When the two subscribers replace their receiver after a talking connection has been established in the above-described manner the disconnect is effected as follows: When the calling station S^1 hangs up the line relay AR is deenergized and this in turn deenergizes the auxiliary relay TR which in turn deenergizes the relay Te^1 of the calling line connector CC^1 , Fig. 1, in the manner already

described when the operations that occurred on the wanted line being found busy were dealt with. The deenergization of Te^1 results in the deenergization of the relay Te^1 of the wanted line connector WC^1 , Fig. 8. 70 The relay Te^1 then opens at its contact 465 the circuit of the relay He^1 and also the circuits of the relays Pe^1 and 658 of the wanted line connector WC^1 . When the armature of the relay Pe^1 drops back it closes at its contact 472 the circuit of the release magnet Me^1 which thereupon restores the wanted line connector WC^1 to normal. This does not affect the relays AR^1 TR^1 as these relays are deenergized only when the wanted subscriber 80 hangs up. When the wanted subscriber does this the relay AR^1 is deenergized and opens at its contact 454 the circuit of the relay TR^1 . If the calling subscriber had not hung up and the wanted line connector WT^1 had not been restored the following events would now occur. The release relay MR^1 in the connector WC^1 would be energized by a circuit extending from the positive pole through the winding 450 of the relay TR^1 , 90 contact 449 of the relay AR^1 , wire 448, 447, bank contact 445, wiper 444 of the connector WC^1 , wire 443, winding 520 of the relay MR^1 , contact 519 of the relay 658 to the negative pole of the battery. The relay MR^1 in this circuit would now be energized and close a locking circuit for itself at its contact 587 which is independent of the relay Te^1 . The relay MR^1 closes at its contact 95 523 a circuit which extends from the positive pole of the battery through the off-normal contact 474, release magnet Me^1 , wire 473, contact 524 of relay Pe^1 , contact 522 of the relay He^1 , contact 523 of the relay MR^1 to the negative pole of the battery. The magnet Me^1 in this circuit is then energized and restores the wanted line connector WC^1 to its normal position. If, during the time that the magnet Me^1 is energized, the relay Te^1 and consequently also the relay MR^1 should 100 be deenergized by the calling subscriber S^1 replacing his receiver, the release magnet Me^1 would keep itself energized by means of its own contact 525 until the off-normal contact 474 is opened by the wanted line connector WC^1 reaching its normal position. 105

In case the wanted line connector WC^1 is released by the wanted subscriber S^1 , the calling line connector CC^1 and trunk connector TC^1 will be released by the calling subscriber S^1 as already described and, on the relay Te^1 of the wanted line connector WC^1 which has already been released being deenergized it will open at its contact 465 the circuits of the relays He^1 , Pe^1 , MR^1 and 658. 115 The apparatus will then have been completely restored and made available for a new connection.

120 The circuits will now be described which operate when a calling subscriber is prevent- 130

ed from obtaining a connection because the switches of the dialling trunks or also of the talking trunks are all engaged when he makes his call.

When the subscriber S^1 raises his receiver at a time when all the calling line finders CF of his group are engaged a circuit will be closed for a blocking relay Sp , Fig. 2, this circuit comprising a chain of connections that extend through all of the calling line finders CF in the group of the calling subscriber and consisting of the wires 540, 541, contact 542, wire 543, contact 544 etc. The blocking relay Sp in this circuit is energized and through its contact 591 it connects the busy signal producer BSu to a coil associated with the line relay of the calling line. This busy signal circuit extends through 591, 592, 593, Fig. 1, wire 595, contacts 596 and 597 of the marginal relay TR of the calling line, coil i of the relay AR . A busy tone current is thus induced in the calling subscriber's line and intimates to the calling subscriber that he must wait until the busy signal disappears before sending in his dialling impulses.

If, at the time a subscriber makes a call, all the trunks CC' , TC of the calling subscriber's group are engaged the blocking relay Sp will also be energized by a chain of connections that extends through all of the calling line connectors and the trunk connectors TC of the calling subscriber's group. The circuit through the blocking relay Sp will extend from the negative pole through the relay Sp , wire 105, 106, Fig. 1, contact 107, wire 108 and then partly through the wire 110, 111, Fig. 3, contact 112, 113 and partly through the wire 116, Fig. 1, wire 117, contact 109, Fig. 1 and through the contact 115, Fig. 3 to the positive pole.

If a calling subscriber S^1 gets through to the group selector finders GF of the wanted group, via a group selector GS and the group selector finders GF in the wanted group should all be engaged a circuit will be established through a chain of connections that extends through all of the group selector finders GF in that particular group. This circuit will extend from the negative pole of the battery through the blocking relay Sp , wire 540, 545, 546, Fig. 4, wires 547, 548, 549, 551, wiper 552, the bank contact of the group selector GS engaged by this wiper, say contact 553, wire 554, 555, Fig. 7, wire 556, contact 557, wire 558, contact 559, wire 560 to the positive pole of the battery. If no trunks should be available when a call has been extended to the wanted group a circuit will be established for the blocking relay Sp through a chain of connections that extends through all the wanted line connectors WC of the wanted group. This circuit will extend over the path just described to the wire 555 and then through 561 relay SR ,

Fig. 6, wire 562, 563, Fig. 8, wire 564, 565, contact 566, wire 567, contact 568 to the positive pole of the battery.

The current flowing in this circuit will energize not only the blocking relay Sp but also the relay SR , Fig. 6 and the latter relay will disconnect the interrupter Ub from the driving magnets Df and Ds of the pairs of finders $AF-ST$, Fig. 6, and thus prevent useless movements of these finders. In all the said cases the blocking relay Sp connects the busy signal producer BSu through its contact 591 to the induction coil i of the line relay AR of any calling subscriber. Subscribers who have already obtained a connection will not get the said busy signal because the marginal auxiliary relays TR associated with their lines will be completely energized so that their contacts corresponding to 597 will be open to prevent the busy tone current from flowing into the coils i of their line relays. The blocking relay Sp also disconnects the interrupter Ub from the lead 92, 93, 94 and 612 to prevent useless energizations of the driving magnet of the primary trunk Pt .

It will be evident that by making obvious changes in the circuits of the calling line finders CF group selectors GS Fig. 4, group selector finders GF , Fig. 7, and the wanted line selectors WS , Fig. 9, these switches might be used not only for dialling purposes but also for effecting talking connections. The separate talking connection switches and trunks in Figs. 8, 9, 3 and 1 could then be omitted. It will also be obvious that the battery used may be common to the whole exchange and that the interrupter Ub , the busy tone producer BSu and free signal producer FSu may also be common to all the circuits in the exchange.

I claim:

1. In a telephone exchange system, a plurality of lines, a plurality of group selector switches, means responsive to the initiation of a call for establishing a connection between the calling line and one of said switches, means controllable over said connection for operating said group selector switch in accordance with one digit of the called number, a wanted line selector, means for connecting said wanted line selector with the operated group selector switch, means operable in accordance with a further digit of the called number for actuating said wanted line selector to select the called line, a plurality of primary and groups of secondary trunks, means for connecting one of said primary trunks with the calling line, means operable in accordance with said one digit of the called number for selecting a certain group of secondary trunks, means for connecting said primary trunk with a certain secondary trunk in the selected group, a wanted line connector associated with the se-

lected secondary trunk, means for causing said wanted line connector to connect with the wanted line selected by said wanted line selector, and a talking connection between the calling and called lines established through said primary and secondary trunks.

2. In a telephone exchange system, a plurality of lines, a plurality of group selector switches, means responsive to the initiation of a call for establishing a controlling circuit between the calling line and one of said switches, means controllable over said circuit for operating said group selector switch in accordance with one digit of the called number, a plurality of wanted line selectors, means for connecting a wanted line selector with the operated group selector switch, means operable through said controlling circuit in accordance with a further digit of the called number for actuating said wanted line selector to select the called line, a plurality of primary and groups of secondary trunks, means for connecting one of said primary trunks with the group selector taken into use,

means for connecting said primary trunk with the calling line, a trunk connector, means operable in accordance with said one digit of the called number and controlled over said controlling circuit for operating said trunk connector to select a group of secondary trunks, means operable upon the connection of said group selector with a wanted line selector for causing said trunk connector to connect said primary trunk with a certain secondary trunk in the selected group, a wanted line connector associated with the selected secondary trunk, means for initiating the operation of said wanted line connector prior to the completed setting of said

wanted line selector, means for causing said wanted line connector to connect with the wanted line selected by said wanted line selector, and a talking connection between the calling and called lines established through said primary and secondary trunks.

3. In a telephone exchange system, a plurality of lines, a plurality of calling line finder switches, means responsive to the initiation of a call for actuating one of said switches to connect with the calling line, a group selector switch associated with the actuated calling line finder switch, means controllable through the calling line for operating said group selector switch in accordance with one digit of the called number, a plurality of group selector finder switches, a plurality of wanted line selectors, means for operating one of said group selector finder switches to connect a wanted line selector with the operated group selector switch, means operable through said calling line in accordance with a further digit of the called number for actuating the connected wanted line selector to select the called line, a plurality of primary and

groups of secondary trunks, a primary trunk selector switch for connecting a primary trunk with the group selector taken into use, means for connecting said primary trunk with the calling line, a trunk connector, means operable in accordance with said one digit of the called number and controlled over said primary trunk selector for operating said trunk connector to select a certain group of secondary trunks, finder switches controlled over said group selector finders for causing said trunk connector to connect said primary trunk with a certain secondary trunk in the selected group, a wanted line connector associated with the connected secondary trunk, means for initiating the operation of said wanted line connector prior to the completed setting of said wanted line selector, means for causing said wanted line connector to connect with the wanted line selected by said wanted line selector, and a talking connection between the calling and called lines established through said primary and secondary trunks.

4. In a telephone exchange system, a calling line, a called line, a selectively operable switching device for connecting with the called line, a relatively slow-acting device operable upon the initiation of a call for extending the calling line toward said switching device, a group selector, a relatively quick-acting device adapted to connect the calling line with said group selector, means for operating said group selector in accordance with the numerical designation of the called line, and a finder switch operable thereupon for connecting said selector with said selectively operable switching device.

5. In a telephone exchange system, a calling line, a called line, a selectively operable switching device for connecting with the called line, a relatively slow-acting line finder operable upon the initiation of a call for extending the calling line toward said switching device, a group selector, a relatively quick-acting line finder adapted to connect the calling line with said group selector, means for operating said group selector in accordance with the numerical designation of the called line, and a finder switch operable thereupon for connecting said selector with said selectively operable switching device.

6. In a telephone exchange system, a calling line, a called line, a plurality of trunks through which a talking connection may be established between said lines, a plurality of other trunks through which a temporary connection may be established between said lines, two selectors, one for selecting one of said trunks and the other for selecting one of said other trunks, and means for simultaneously operating said selectors in accord-

- ance with the numerical designation of the called line.
7. In a telephone exchange system, a calling line, a called line, a plurality of trunks through which a talking connection may be established between said lines, a plurality of other trunks through which a temporary connection may be established between said lines, two selectors, one for selecting one of said trunks and the other for selecting one of said other trunks, and means for simultaneously operating said selectors in accordance with a certain digit of the called number.
8. In a telephone exchange system, a calling line, a called line, a plurality of trunks through which a talking connection may be established between said lines, a plurality of selectors cooperating with said trunks, a plurality of other trunks through which a temporary connection may be established between said lines, a plurality of other selectors cooperating with said other trunks, means for selecting an idle one of said selectors for operation and for connecting it with the calling line, means for connecting an idle one of said other selectors with the calling line, means for simultaneously operating the two selected selectors in accordance with the numerical designation of the called line, and means for extending the operated other selector towards the called line.
9. In a telephone system, a plurality of subscribers' lines, a plurality of trunks, a trunk selector, means for connecting said selector with a calling line, connectors for extending said trunks to called lines, a plurality of switching devices, means for operating said devices in accordance with the numerical designation of a called line to control the operation of said connector, a plurality of group selectors, means for connecting one of said group selectors with the calling line, means for operating said group and trunk selectors in accordance with the numerical designation of a called line, a finder switch associated with each one of said switching devices, means for operating said finder switches to connect one of said devices with an operated group selector, and hunting switches for connecting said finder switches with said trunks.
10. In a telephone system, a plurality of subscribers' lines, a plurality of trunks, a trunk selector, means for connecting said selector with a calling line, connectors for extending said trunks to called lines, a plurality of switching devices, means for operating said devices in accordance with the numerical designation of a called line to control the operation of said connector, a plurality of group selectors, means for connecting one of said group selectors with the calling line, means for operating said group
- and trunk selectors in accordance with the numerical designation of a called line, a finder switch associated with each one of said switching devices, means for simultaneously causing said finder switches to operate, means for stopping one of said finder switches to connect one of said devices with an operated group selector, and pairs of hunting switches for connecting the stopped finder switch with said trunks.
11. In a telephone system, a plurality of subscribers' lines, a plurality of trunks, a trunk selector, means for connecting said selector with a calling line, connectors for extending said trunks to called lines, a plurality of switching devices, means for operating said devices in accordance with the numerical designation of a called line to control the operation of said connector, a plurality of group selectors, means for connecting one of said group selectors with the calling line, connecting means between said group and trunk selectors, means for operating said group and trunk selectors in accordance with the numerical designation of a called line, a finder switch associated with each one of said devices, means for operating said finder switches to connect one of said devices with an operated group selector, pairs of hunting switches for connecting said finder switches with said trunks, and an identifying circuit including a group selector, a trunk selector, a finder switch, a pair of hunting switches, and said connecting means.
12. In a telephone exchange system, a calling line, a called line, a selectively operable switching device for connecting with the called line, a relatively slow-acting device operable upon the initiation of a call for extending the calling line towards said switching device, a plurality of group selectors, a plurality of relatively quick-acting devices, means for simultaneously operating said quick-acting devices upon the initiation of a call, means for causing one of said devices to connect the calling line with an idle one of said group selectors, a plurality of finder switches, means for operating said group selectors in accordance with the numerical designation of the called line, means operable thereupon for simultaneously actuating said finder switches, and means for causing one of said finder switches to connect the operated group selector with said switching device.
13. In a telephone exchange system, a calling line, a called line, a selectively operable switching device for connecting with the called line, a relatively slow-acting line finder operable upon the initiation of a call for extending a calling line towards said switching device, a plurality of group selectors, a plurality of relatively quick-acting line finders, means for simultaneously

- operating said quick-acting finders upon the initiation of a call, means for causing one of said quick-acting finders to connect the calling line with an idle one of said group 5 selectors, a plurality of finder switches, means for operating said group selectors in accordance with the numerical designation of the called line, means operable thereupon for simultaneously actuating said finder 10 switches, and means for causing one of said finder switches to connect the operated group selector with said switching device.
14. In a telephone exchange system, a plurality of calling lines, a plurality of 15 called lines automatic switches, two sets of contacts in each switch, means for operating said switches in accordance with the designations of called lines whereby calling and called lines are interconnected by causing 20 contacts of one set to come into engagement with contacts of the other set, and a test circuit for two of said switches extending over contacts belonging to both sets in both switches.
- 25 15. In a telephone system, a plurality of calling lines, a plurality of called lines automatic switches, means for operating two of said switches in accordance with the same digit of a called line number, and 30 means including a plurality of hunting switches for establishing a test circuit including both said switches.
16. In a telephone exchange system, a plurality of lines, means including a finder 35 and a selector switch for interconnecting
- said lines, a plurality of wipers for said finder, a test relay associated with each wiper, a common current lead for said test relays, a relay controlling the continuity of said lead, and an operating circuit for said 40 last mentioned relay controlled by said test relays.
17. In a telephone exchange system, a plurality of lines, a selector switch for interconnecting said lines, a plurality of 45 wipers for said selector, a test relay associated with each wiper, a common relay controlling the circuits of said test relays, and a circuit for said common relay controlled by said test relays. 50
18. In a telephone exchange system, a plurality of lines, means including a selector switch for interconnecting said lines, a plurality of wipers for said selector, a test relay having high and low resistance windings 55 associated with each wiper, a conductor multiplied to the high resistance windings of said test relays, a common relay having high and low resistance windings controlling the continuity of said conductor, an 60 energizing circuit for both windings of said last mentioned relay controlled by said test relays, and means operable upon the energization of any one of said relays for closing a shunt path to its high resistance 65 winding.

In testimony whereof I have signed this specification.

FRITZ ALDENDORFF.
